UNITED STATES PATENT OFFICE.

JOHN HENRY PAUL HANEKLAUS, OF PALMER, IOWA.

DECOY-SHIP.

1,182,874.

Specification of Letters Patent.

Patented May 9, 1916.

Application filed September 4, 1915. Serial No. 48,970.

To all whom it may concern:

Be it known that I, JOHN HENRY PAUL HANEKLAUS, a citizen of Germany, residing at Palmer, in the county of Pocahontas and 5 State of Iowa, have invented certain new and useful Improvements in Decoy-Ships, of which the following is a specification.

My invention relates to a class of target ships or boat decoys, which are adapted to 10 draw the fire from the enemy's guns, misleading them as to the location of the real or material ship, and having for its object the provision of such a floating target or decoy which will adapt itself to the high 15 seas, and at the same time, being so disposed and constructed as to collapse when desired, so that it may occupy as limited a space as possible when carried aboard ship, or so that it will present little or no trouble when put 20 in tow by a smaller ship. Having these and other objects of general utility in view, I have illustrated a practical embodiment of my invention in the accompanying drawing, in which—

25 Figure 1 is a broad side elevation of my target with the picture canvas or screen in operative position; Fig. 2 is a top plan thereof; Fig. 3 is a front elevation thereof, showing the extended position of the two 30 pontoons, and Fig. 4 is an enlarged sectional detail of the butt-joint connection employed, taken on line 4—4 of Fig. 3 as indicated by the arrows.

Similar reference characters refer respectively to similar parts throughout the several views.

My invention consists primarily in providing a floating screen or canvas 5, adapted to receive stereopticons projected thereon 40 from the usual form of cinematograph or stereopticon machine, 25. The screen is carried upon a plurality of vertical masts or guides 6, securely fastened to the deck 7 of a pontoon or float 8. In order to lend distance between the projecting machine and the screen, I prefer to mount the machine 25 upon a suitable pedestal 9, carried by an auxiliary float 10, lying parallel to the float

8, and connected thereto by means of a set of pivoted paralleling arms 11—12, pivotally connected at 13 to the sleeve 14, to provide the common form of butt-joint (Fig. 4) therebetween. The opposite ends of the arms 11 are pivoted at 15—15 to the deck of the float 10, and the opposite ends 55 of the arms 12 are pivoted at 16—16 upon the deck 7 of the float 8; keyed to these pintles 16 are beveled gears 17—17, meshing with gears 18—18 which are adapted to be rotated upon their common shaft 19, by 60 means of a hand wheel 20.

It will now be apparent, that after the floats have been towed to their position, the operator will turn the hand wheel 20, rotating the shaft 19 and causing the rotation 65 of the meshing gears 17 and 18, and thus causing the arms 12 to pivot toward each other, forcing the float 10 from the float 8, but keeping parallel thereto, thus giving the projecting machine distance to throw 70 the picture of a battleship upon the screen 5, and draw the attention and fire from the enemy's guns.

What I claim is:—

1. A decoy ship comprising a floating canvas and a projecting machine in conjunction therewith. 75

2. A decoy ship comprising two parallel disposed floats, a screen mounted upon one of said floats, and a projecting machine 80 mounted upon the other of said floats and adapted to throw pictures upon said screen.

3. A decoy ship comprising two floats, means for paralleling said floats and moving same with respect to one another, a 85 screen mounted upon one of the said floats, and a projecting machine mounted upon the other of said floats.

In testimony that I claim the foregoing as my own I have hereto affixed my signature 90 in the presence of two subscribing witnesses.

JOHN HENRY PAUL HANEKLAUS.
